TENSION CONTROLLING MEANS FOR STRIP MATERIAL

George Thomas Wilson Grieve, Woolwich, London, England, assignor to British Insulated Callender's Cables Limited, London, England, a British company

Application June 30, 1951, Serial No. 234,505
In Great Britain July 7, 1950

6 Claims. (Cl. 57—3)

1

When a strip of paper, a length of yarn, or wire or other long flexible member is being drawn from or wound on to a reel, bobbin or other support, there is frequently the necessity for keeping the tension in the member approximately constant. Some cases require a greater degree of accuracy and constancy in this than others and in some cases there is more tendency to variation of tension and variation over a larger range than in others. One of the most difficult cases, from both these points of view, is found in the lapping of paper tape on to an electric conductor for the purpose of building-up a body of insulating material. It is with this case that the invention is primarily concerned but it is also applicable to other cases.

In lapping paper tape on to an electric conductor the tape in the form of a flat spiral coil or pad is held on a spindle between discs and the whole is rotated bodily about the axis of the cable, the paper tape being drawn off over suitable guides so as to be lapped helically with precision about the conductor. Tension is applied to the tape at the pad holder by the bearing friction and by a brake. It is also applied by friction at the guides. The total tension is produced by a combination of these effects in varying proportions according to the design of machine and to the particular conditions of operation.

By the nature of this case there are two principal causes operating to produce variation in the tension in the paper. One of these is the change in the diameter of the pad; a constant tension in the paper at the periphery of the pad obviously cannot be balanced by a constant braking force on the pad carrier as the radius of application of the tension to the pad varies through a large range. The other principal cause is the change of centrifugal loading on the bearings of the pad and of the guides as the speed of rotation about the axis of the cable changes during starting and stopping of the machine.

The present invention deals with the first of these two causes and it will be seen that it is applicable, not only to the particular case for which it is primarily intended but also to other cases where the diameter of the coil varies during the withdrawing of the flexible member from it.

For convenience the flexible member will be hereinafter referred to by the word "tape," it being understood that this word is only used as illustrative of a general class of long flexible articles.

In accordance with the invention the loading

of the brake on the carrier of the coil is adjusted by means of a mechanical relay device, the action of which is under the control of the tension which exists in the tape. This relay action is provided by a rotary shaft in continuous motion which can be coupled from time to time with means for adjusting the brake, the time of coupling and the sense of its effect in producing adjustment being determined by the action of a feeler member 10 which is subjected to the tension of the tape. A preferable arrangement is one in which the shaft carries or actuates a cam or other means of producing reciprocating motion having a free interval in each cycle of movement and the adjustment of the brake loading is produced by a turning of a member, such as a nut or cam, which may be moved in either sense by the action of pawls and ratchet wheels, the pawls being coupled to a reciprocating member or brought into association 15 with the ratchet wheel, during free intervals, by the feeler member under the influence of the tension in the tape.

The feeler arrangement may consist of a roller round which the tape passes and which is carried 20 at the end of a swinging lever, the position of which is determined by the balance between the tension on the tape acting on the roller and the force of a spring acting on the lever in opposition to the tension. The tape is preferably guided by 25 the aid of two other rollers so that it passes in a narrow loop from these two rollers round the feeler roller which is in the end of the loop, so that the direction of the force exerted by the tension in the tape does not vary appreciably with the movement of the feeler roller. The spring force may be provided by an independent spring acting on a pivoted lever or by the inherent springiness of a lever which is firmly anchored at the end remote from the feeler.

With a controlling arrangement in accordance 30 with the invention, the adjustment of the brake loading, while it may vary to some extent in both senses, will, in general, change as the coil of paper decreases in diameter in such a way that the loading of the brake decreases progressively. It will, accordingly be necessary to reset the loading when a new coil is placed in position. This can be done by hand or automatically and in the latter case may result from some action 35 involved in the placing of new coil in position. For instance, when the coil carrier or a movable part thereof is removed from or replaced in position with or after the insertion of the new coil, its movement out of or into place may produce 40 by means of suitable gearing the readjustment

of the brake loading to the approximate value required.

In a machine for lapping paper tape on to an electric conductor in which the coil of paper is carried in rotation about the axis of the machine while the conductor moves forward along that axis, the mechanical relay device can be provided by a cam which is mounted about the axis of the machine and is either held stationary or is rotated at a speed different from, but proportional to, that of the head carrying the coils of paper. The cam is shaped to provide a part or parts at which it is disengaged from its follower to give free intervals in the transmission.

An example of a machine for lapping paper tape onto an electric conductor will be described as an example with reference to the accompanying drawings in which Figure 1 is an elevation of part of the machine and Figure 2 is a side elevation partly in cross-section of some parts of the machine shown in Figure 1. Figures 3 to 6 represent parts of the arrangement shown in Figure 1. Figure 3 shows also an arrangement for driving the machine, and Figures 4 to 6 represent details to a larger scale.

The machine is of the type in which the coil 1 of the paper tape rotates bodily, in a suitable carrier, about the axis of the conductor with its central plane substantially radial to the axis of the conductor. The coil 1 is mounted between two metal discs 2 and 3 (Figure 2) on a hub 4 carried by a spindle 5. The spindle 5 is freely supported in ball bearings 6 at the end of a vertical arm 7 rigidly mounted on the end of a horizontal spindle 8. The horizontal spindle 8 is securely anchored by nuts 9 to a support 10 which rotates about a fixed tubular hub 11. The support 10 is fixed to a sleeve 52 surrounding the fixed hub 11 and mounted for rotation in a bearing 53 which is supported on a pedestal 54. The drive to the rotating sleeve 52 is derived from a motor 55, through a gear box 56, driving shaft 57, gear wheel 58, driving chain 59 and driven gear wheel 60 fixed to the sleeve 52. The conductor onto which the paper is being lapped passes centrally through the tubular hub 11.

A toothed ring 12 secured to the hub 11 by a pin 61 meshes with a gear wheel 13 mounted coaxially with a second smaller gear wheel 14 on a spindle 15 fixed to the rotating part of the machine. The spindle 15 is supported in a bearing plate 62 which is fixed to a plate 22 attached to the sleeve 52. The smaller gear wheel 14 drives a second toothed ring 16 which is loosely mounted on a bearing 63 in suitable guides on the hub 11. It will be seen that the two gear wheels 13 and 14 being fixed together act as a reduction gear to drive the wheel 16 at an angular speed less than that of the sleeve 52 and associated rotating parts.

The wheel 16 is formed with a tubular extension 17 to which is secured a cam ring 18. A tappet rod 19 is freely mounted for longitudinal reciprocation in guides 20 supported on the plate 22 which rotates with the support 10. Fixed to the lower end of the rod 19 is a roller 23 which is forced against the surface of the cam 18 by a spring 21 and fixed to the upper end of the rod 19, there is a flat bracket 24 on which slides a block 25 fixed at 67 to a horizontal rod 26.

The position of the block 25 is controlled by the horizontal rod 26 which passes freely through holes 64 in the vertical arms 65 of the bracket 24 and is coupled at its opposite end to a pivoted arm 27 carried by the arm 7. The coupling be-

tween the horizontal rod 26 and the pivoted arm 27 is a pivot 66 which allows the rod 26 to move freely in a vertical plane. The arm 27 is biased by a spring (not shown), which tends to rotate it in a clockwise direction. Paper tape 28 passes from the coil 1 over a guide roller 29 secured to the arm 7, then over a roller 30 carried at the lower end of the arm 27 and back under a third roller 31 to further guide rollers, not shown, which direct it onto the conductor. The arm 27 and roller 30 constitute a "feeler member" responsive to the tension of the tap 28. Increase in tension in the tape 28 will tend to move the roller 30 towards the arm 7, hence pivoting the arm 27, against the biasing spring, in an anti-clockwise direction to force the block 25 towards the left-hand end of the bracket 24. Similarly, a decrease in tension in the tape will allow the arm 27 to rotate in a clockwise direction under the action of the biasing spring to move the block 25 towards the right-hand end of the bracket 24.

Two opposed ratchet wheels 32 and 33 (that is wheels having their teeth arranged in opposite senses) are loosely mounted, integrally with each other and with a bevel gear wheel 34, on the horizontal spindle 8. The bevel gear wheel 34 drives a smaller bevel gear wheel 37 which is attached to a cam 38. The ratchet wheel 32 is rotatable by a pawl 35 and the ratchet wheel 33 by a pawl 36 (see Figure 2). The tappet rod 19 is continually reciprocated under the action of the cam 18 when the sleeve 52 and the parts carried on it, including the paper coil 1 are rotating about the conductor.

When the block 25 is in a central position on the bracket 24, as shown in the drawing, it does not make contact with either of the pawls 35 and 36 during the reciprocating movement of the rod 19 but when it is moved to the right or left as tension in the tape 28 varies, it makes contact, as the rod 19 moves upwards, with one of the pawls 35 and 36 and rotates the corresponding ratchet wheel about the spindle 8. The horizontal rod 26 is long in comparison with the range of movement of the tappet rod 19 so that the path of the block 25 approximates sufficiently to a straight line.

The major part of the periphery of the cam ring 18 is circular, as shown at 68 in Figure 5 and when this part is uppermost the ring does not make contact with the roller 23. The effective lobe 69 of the cam ring 18 extends over a relatively small area as shown in Figure 5. The downward movement of the tappet rod 19 under the influence of the spring 21 is limited by the engagement on the top of the upper fixed guide 20 of the underside of a nut 70 which locks the connection between the tappet rod and the bracket 24. This ensures that there is a free interval in each cycle of movement of the tappet 19 when it is at rest in its lower position. In this position the block 25 is free to move from end to end of the bracket 24 with movement of the arm 27 unimpeded by the lower ends of the pawls 35 and 36.

The brake drum 39 is rigidly mounted on the same spindle 5 as the hub 4, which carries the coil 1. A brake shoe 40 carried on a pivoted arm 41 is forced into contact with the outer surface of the drum 39 by a biasing spring 42 acting upon a collar 43 rigidly secured to a brake rod 44. The end of this brake rod bears against the surface of the cam 38. When the end of the brake rod 44 makes contact with the lowest part

of the cam 38, the position shown in Figure 4, the maximum braking is applied to the drum 39 by the shoe 40 under the action of the spring 42. As the cam 38 is rotated counter-clockwise as seen in Figure 4, under the action of the pawl 35 and its associated ratchet 32, the braking effect is decreased by the movement of the brake rod 44 towards the righthand as seen in the drawing; under the action of the other pawl 36 and its associated ratchet wheel 33, the cam 38 is rotated in the reverse direction so that the braking is increased. The operative surface of the cam 38 is of spiral shape the highest and lowest points 71 and 72 respectively being connected by a radial step 73.

At the start of a lapping operation when a full coil of tape is loaded on the hub 4, the cam 38 is initially set with its lowest part 72 adjacent the end of the brake rod 44 so that maximum braking is applied. Generally as the tape is unwound from the coil, it will be necessary for progressively decreasing braking to be applied to the drum 39 to maintain a uniform tension in the tape 28 as the diameter of the coil decreases. As the tension in the strip tends to increase with the decrease in coil diameter the braking effect of the shoe 40 on the drum 39 will be appropriately altered, to maintain the correct tension, by the pivoting of the feeler member 27 and the sliding of the block 25 in the bracket 24 to cause the reciprocating tappet rod 19 to reciprocate the appropriate pawl 35. Should the tension in the strip tend to decrease due for instance to uneven winding of the coil the reverse effect will be obtained by means of the other pawl 36.

Means are provided for automatically rotating the cam 38 into a position in which its lowest part is adjacent the end of the brake rod 34 whenever a new coil of paper is loaded onto the hub 4. This is effected by the following mechanism. A spindle 45 (Figure 2) passes centrally through the spindle 5 on which the coil is mounted. The spindle 45 is associated with means, not shown, as described in the specification of co-pending U. S. Patent application Serial No. 234,492 filed June 30, 1951 of Ripley, which serves for releasing a spent coil from and locking a new coil on the hub 4. During this operation the spindle 45 is rotated in a clockwise direction and then in a counter clockwise direction as seen in Figure 1. A disc 46 mounted on the end of the spindle 45 inside the brake drum 39 carries a projecting pin 47 which, upon this rotating movement of the spindle 45, is brought into contact with a spring 48 mounted on a vertical arm 49. The arm 49 is rigidly attached to a horizontal rod 50 adapted to bear against a pin 51 projecting upwards from the upper face of the cam 38. The rotation of the spindle 45 in a clockwise direction under these conditions, forces the rod 50 from right to left and rotates the cam 38 to a position in which its lowest part bears against the end of this rod. Thus this action resets the brake 40 into a position into which it exerts the maximum braking force on the drum 39.

In normal operation of the machine the successive coils of strip which are used will have approximately similar characteristics of diameter and winding tension. In normal running therefore the brake rod 44 will be in contact with the cam 38 at or near the highest point 73 when a coil requires replenishing. The angular position of the pin 51 relative to this

point 73, the diameter of the pin, its radial distance from the centre of rotation of the cam, and the limit of movement of the end 75 of the horizontal rod 50 towards the lefthand are so selected that at the end of the movement of the rod 50 the cam will have turned to the position in which the end of the brake rod 44 will fall from the highest point 73 to the lowest point 72. In practice the coil of strip will be replenished before the highest point 73 of the cam is reached and the automatic resetting of the cam will take place when the pin 51 comes to a final position anywhere within the arc 74. If for any reason the pin lies outside that arc the cam will be turned to the appropriate position by the tension controlling mechanism after rotation of the machine is resumed.

What I claim as my invention is:

1. Apparatus for controlling the tension in a long flexible member while it is being unwound from a carrier comprising a brake retarding said carrier, a shaft driven in continuous rotary motion throughout the winding or unwinding operation, means for adjusting said brake, a feeler member subjected to the tension of said flexible member and means controlled by said feeler member for intermittently coupling said shaft with said brake adjusting means to effect the adjustment of the brake necessary when said tension changes from the desired value.

2. Apparatus for controlling the tension in a long flexible member while it is being unwound from a carrier comprising a brake retarding said carrier, a shaft driven in continuous rotary motion throughout the unwinding operation, a reciprocating member driven by said shaft, two opposed ratchet wheels, a rotatable member adapted to be driven in a direction to decrease said braking by the first of said ratchet wheels and in a direction to increase said braking by the second of said ratchet wheels, first and second pawls one associated with each of said ratchet wheels, a feeler member subjected to the tension of said flexible member and adapted to adjust said brake by coupling said first pawl to said reciprocating member when the tension increases excessively and said second pawl to said reciprocating member when the tension decreases excessively.

3. Apparatus for applying a lapping at a substantially uniform tension of a long flexible member to a second member passing through said apparatus comprising a carrier for said flexible member, means for rotating said carrier bodily about said second member, a brake retarding the delivery of said flexible member from said carrier, a reciprocating member driven in such a way that there is a free interval in each cycle of its movement by said rotation of said carrier about said second member, two opposed ratchet wheels, a rotatable member adapted to be driven in a direction to decrease said braking by the first of said ratchet wheels and in a direction to increase said braking by the second of said ratchet wheels, first and second pawls one associated with each of said ratchet wheels, a feeler member subjected to the tension of said flexible member and adapted to adjust said brake by bringing said first pawl into association with said reciprocating member during a free interval when the tension increases excessively and bringing said second pawl into association with said reciprocating member during a free interval when the tension decreases excessively.

4. Apparatus for applying a lapping at a sub-

stantially uniform tension of a long flexible member to a second member passing through said apparatus comprising a carrier for said flexible member, means for rotating said carrier bodily about said second member, a brake retarding the delivery of said flexible member from said carrier, a reciprocating member driven in such a way that there is a free interval in each cycle of its movement by said rotation of said carrier about said second member, two opposed ratchet wheels, a rotatable member adapted to be driven in a direction to decrease said braking by the first of said ratchet wheels and in a direction to increase said braking by the second of said ratchet wheels, first and second pawls one associated with each of said ratchet wheels, a feeler member subjected to the tension of said flexible member and adapted to adjust said brake by bringing said first pawl into association with said reciprocating member during a free interval when the tension increases excessively and said second pawl into association with said reciprocating member during a free interval when the tension decreases excessively and means for automatically resetting said brake to the position of maximum braking whenever a fresh supply of said flexible member is loaded onto said carrier.

5. Apparatus for lapping at a substantially uniform tension, a flexible tape onto a conductor, comprising a carrier for a coil of said tape, means for rotating said carrier and coil bodily about said conductor, a brake retarding the unwinding of said tape from said coil, a reciprocating member driven by said rotation of said carrier about said second member, two opposed ratchet wheels, a rotatable member adapted to be driven in a direction to decrease said braking by the first of said ratchet wheels and in a direction to increase said braking by

10 the second of said ratchet wheels, first and second pawls one associated with each of said ratchet wheels, a feeler member subjected to the tension of said flexible member and adapted to adjust said brake by coupling said first pawl to said reciprocating member when the tension increases excessively and said second pawl to said reciprocating member when the tension decreases excessively.

15 6. Apparatus for lapping at a substantially uniform tension, a flexible tape onto a conductor, comprising a carrier for a coil of said tape, means for rotating said carrier and coil bodily about said conductor, a brake retarding the unwinding of said tape from said coil, a reciprocating member driven in such a way that there is a free interval in each cycle of its movement by said rotation of said carrier about said second member, two opposed ratchet wheels, a rotatable member adapted to be driven in a direction to decrease said braking by the first of said ratchet wheels and in a direction to increase said braking by the second of said ratchet wheels, first and second pawls one associated with each of said ratchet wheels, a feeler member subjected to the tension of said flexible member and adapted to adjust said brake by bringing said first pawl into association with said reciprocating member during a free interval when said tension increases excessively and bringing said second pawl into association with said reciprocating member during a free interval when said tension decreases excessively, and means for returning said rotatable member to the position of maximum braking actuated when a new coil is placed in position on said carrier.
